FOREIGN PATENT DOCUMENTS

GB 2391292 4/2004

Primary Examiner—Holly H. Bayham*Assistant Examiner*—Cynthia M. Chin(74) *Attorney, Agent, or Firm*—Keisling Pieper & Scott PLC; David B. Pieper; Trent C. Keisling(57) **CLAIM**

The ornamental design for a trigger assembly, as shown and described.

DESCRIPTION

FIG. 1 is a left side view of a trigger assembly showing my new design.

FIG. 2 is a top view of a trigger assembly showing my new design.

FIG. 3 is a right side view of a trigger assembly showing my new design.

FIG. 4 is a bottom view of a trigger assembly showing my new design.

FIG. 5 is a back view of a trigger assembly showing my new design; and,

FIG. 6 is a front view of a trigger assembly showing my new design.
